Primary Examiner — Angela J Lee*Assistant Examiner* — Anthony Vincent Rotolo(74) *Attorney, Agent, or Firm* — Meunier Carlin & Curfman LLC(57) **CLAIM**

The ornamental design for the light emitting diode, as shown and described.

DESCRIPTION

FIG. 1 is a front, left and top side perspective view of the light emitting diode showing my new design;

FIG. 2 is a rear, right and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.
